UNITED STATES PATENT OFFICE

134,118

DESIGN FOR A DECK OF PLAYING CARDS

Claude S. Demorest, Oteen, N. C.

Application May 4, 1942, Serial No. 106,791

Term of patent 14 years

To all whom it may concern:

Be it known that I, Claude S. Demorest, a citizen of the United States, residing at Oteen, in the county of Buncombe and State of North Carolina, have invented a new, original, and ornamental Design for a Deck of Playing Cards, of which the following is a specification, reference being had to the accompanying drawings, forming part thereof.

The Figures 1, 2, 3, 4, 5, 6 are face views of the cards of the deck, showing my new design. The backs of the cards are conventional.

I claim:

The ornamental design for a deck of playing cards, as shown and described.

CLAUDE S. DEMOREST.
